(57) **ABSTRACT**

A protective furnace gas for protecting a bath of magnesium in furnace equipment includes a mixture of inert gas such as nitrogen and 0.3 to 1.5% by volume of SO₂, the mixture being provided in a temperature-controlled room wherein the temperature is at least 22° C. and preferably 25° to 35° C.

5 Claims, 1 Drawing Sheet

OPERATION METHOD OF FURNACE EQUIPMENT FOR MAGNESIUM ALLOYS

BACKGROUND OF THE INVENTION

The present invention relates to a method for operating furnace equipment for magnesium alloys in which a bath surface is covered with a protective furnace gas containing a sulfur compound.

THE PRIOR ART

In installations where liquid magnesium is present it is necessary to take special precautions to reliably prevent the access of atmospheric oxygen because magnesium is extremely combustible in the liquid state. SF₆ is used as such a protective furnace gas, for example, which reacts with the magnesium of the melt and forms a protective layer which protects the melt from the access of atmospheric oxygen. Occasionally, mixtures of SF₆ and nitrogen are used for this purpose. Since SF₆ concerns a greenhouse gas, its use is problematic for reasons of environmental protection. Moreover, the costs for this gas are relatively high.

It has already been considered as an alternative to use SO₂ as a protective furnace gas. SO₂ is available at relatively low cost and, like SF₆, forms a protective layer on a magnesium melt. The application of SO₂ has been prevented up until now because it concerns an extremely unpleasant smelling gas which in medium to high concentrations is detrimental to health and promotes corrosion. During the use of SO₂ in the conventional manner it is not possible to prevent the escape of gas from the furnaces or the like which leads to an impermissible burden on the ambient environment. In particular, maximum workplace concentrations will be exceeded by far.

It is further known to use gas mixtures of SO₂ and dried air as a protective furnace gas for magnesium furnaces. It has not yet been managed, on the one hand, to control the toxic and corrosive effect of SO₂ and, on the other hand, to realise a secure operation of the furnace.

It is the object of the present invention to provide a method which, on the one hand, allows a secure treatment of magnesium melts and, on the other hand, causes the lowest possible burden on the environment.

SUMMARY OF THE INVENTION

This object is achieved in accordance with the invention in such a way that a mixture of SO₂ and an inert gas is used as a protective furnace gas, with the volume share of SO₂ being set precisely to a value which is in a range of between 0.3% and 1.5%, preferably between 0.5% and 1.0%. It was surprisingly noticed that in the case of SO₂, there is a small range in which there is a sufficient protective effect on the one hand and a burden on the environment can be substantially prevented on the other hand. The relevant aspect of the present invention is the setting of a precise value of the SO₂ concentration in the protective furnace gas. Since very low SO₂ concentrations are used, precise process control and the avoidance of fluctuations in the gas composition is very important to prevent fires.

Nitrogen is used particularly preferably as the inert gas. Nitrogen is available at low cost and is not critical to the environment. In a particularly preferable embodiment of the method in accordance with the invention, it is provided that the mixture of SO₂ and the inert gas is performed in an air-conditioned room whose temperature is kept above 22°

C., and preferably in a range of between 25° C. and 35° C. It has been noticed that a satisfactory mixture of SO₂ and nitrogen is only possible from a certain minimum temperature at a performance pressure >2 bars. Moreover, 5 temperature-induced fluctuations in volume and pressure of the involved gases can be securely prevented by the mixture in an air-conditioned room. A temperature of approx. 30° C. is particularly preferable.

Moreover, the present invention relates to an apparatus for 10 producing a protective furnace gas for furnace equipment for magnesium alloys with a storage tank for a sulfur compound, a storage tank for an inert gas and a mixing device. The apparatus in accordance with the invention is characterized in that the mixing device is arranged to 15 provide a precise flow rate control of SO₂ and nitrogen and is arranged in an air-conditioned room. Safety gas cells are provided in an air-conditioned room which receive the SO₂ cylinders. Nitrogen is taken from a conventional tank. The mixture of SO₂ and nitrogen is performed through electronic 20 mass flow meters which are arranged in the air-conditioned room. The gas mixture thus produced is conveyed to the respective furnace equipment via pipelines and adjusted to consumption by way of local control systems. The furnace equipment can concern smelting furnaces, holding furnaces, dosing furnaces and pig casting belts for magnesium alloys.

SO₂ sensors are provided in the safety gas cells which already respond to low SO₂ concentrations. Once an SO₂ cylinder has been emptied, the same is scavenged with nitrogen together with the pipelines in order to exclude any 30 health hazards during the exchange of the cylinders. In this manner it can be prevented reliably that any SO₂ escapes into the environment.

As a result of the low SO₂ concentration of the protective 35 furnace gas, any pollution of the environment and any annoyance caused by bad smell, particularly in the furnace area, can be securely prevented. Secure operations can be ensured by the precisely set mixture ratio.

BRIEF DESCRIPTION OF THE FIGURE

40 The FIGURE shows a schematic diagram of an apparatus in accordance with the invention.

DETAILED DESCRIPTION OF THE PREFERRED EMBODIMENT

45 Components are described with the broken lines 1 which are arranged in two safety cabinets. Gas cylinders 2 are used as storage vessels for sulphur dioxide which is supplied to a collecting line 4 by way of stop valves 3. A control line 5a is supplied via a manometer 5a which triggers a solenoid valve 6. A supply line 8 for SO₂ is connected via a further stop valve 7.

50 A storage vessel 9 for nitrogen is connected with the distributor line 4 in each of the two safety cabinets 1 via a line 10, a stop valve 11 and a return valve 12 in order to provide nitrogen for scavenging the lines during the exchange of the cylinders 2. A manometer 13 shows the nitrogen pressure in a nitrogen main line 16. The individual cylinders 2 are in connection with a waste gas collecting line 19 via stop valves 17 and waste gas lines 18. The distributor line 4 is vented into the waste gas collecting line 19 via separate stop valves 20. The circuit as described above 55 allows scavenging the respective line sections with nitrogen prior to the exchange of one of the cylinders 2, so that any escape of SO₂ can be reliably prevented.

60 The right-hand section of the FIGURE shows the mixing device for supplying the individual consumers. Since the 65

individual mixers **21** are principally designed in the same way, only one of them is designated with a reference numeral and is described in the description.

The individual mixers **21** are supplied via a first distributor panel **22** with nitrogen and via a second distributor panel **23** with sulphur dioxide. A third distributor panel **24** is used for connecting the mixer **21** with the waste gas collecting line **19**. Stop valves **25** and **26** are provided in the individual mixers **21**, which valves are connected with the distributor panel **22** or **23**. Manometers **27** and **28** indicate the respective nitrogen or sulphur dioxide pressure after the stop valves **25** and **26**. A stop valve **29** for scavenging is provided between the nitrogen line and the sulphur dioxide line, with a return valve **30** being provided downstream of the same. Highly precise flow rate meters **31** for nitrogen and **32** for sulphur dioxide are used for setting the precise quantity ratio for the two gases. Filters **33** and **34** are provided upstream of the flow rate meters **31** and **32**. The gases are joined in a supply line **38** via further stop valves **35** and **36** and a return valve **37**, which supply line is provided with a manometer **39** and a stop valve **40**. A scavenging line **41** with a stop valve **42** is used for preventing any pollution of the environment during maintenance work and the like.

The entire arrangement as exhibited in the FIGURE is arranged in accordance with the invention in an air-conditioned room which is kept at a temperature of approx. 30° C. In this manner the mixture ratio of the gases can be kept at a precisely predetermined value, and a favourable thorough mixture can be ensured.

Flow governors (not shown) can be provided in the individual consumers, which governors only influence the supplied quantity of the gas mixture, but not the composition of the gas.

The present invention thus not only allows savings in costs, but also a substantial reduction of the burden placed on the environment and a particularly safe operation in dealing with magnesium melts.

What is claimed is:

1. A method of protecting magnesium in a bath of magnesium in furnace equipment from contact by ambient air which comprises the steps of:

- 10 (a) providing a temperature-controlled room,
- (b) supplying SO₂ gas to said temperature-controlled room,
- (c) supplying an inert gas to said temperature-controlled room,
- (d) mixing-said SO₂ gas and said inert gas in said temperature-controlled room to provide a protective furnace gas containing 0.3 to 1.5% by volume of SO₂ gas, and
- (e) conveying said protective furnace gas to said furnace equipment containing said bath of magnesium.

2. The method of claim 1, wherein the protective furnace gas provided in step (b) contains 0.5 to 1.0% by volume of SO₂ gas.

3. The method of claim 1, wherein said inert gas in step (c) is nitrogen.

4. The method of claim 1, including a step of controlling the temperature-controlled room to a temperature of above 22° C.

5. The method of claim 4, wherein said temperature is controlled to between 25° and 35° C.
